UNITED STATES PATENT OFFICE.

ANNA E. RUSSELL, OF SYRACUSE, NEW YORK.

VEGETABLE-SLICER.

1,379,724.

Specification of Letters Patent.

Patented May 31, 1921.

Application filed September 28, 1920. Serial No. 412,813.

To all whom it may concern:

Be it known that I, ANNA E. RUSSELL, a citizen of the United States, and a resident of Syracuse, in the county of Onondaga and State of New York, have invented a certain new and useful Vegetable-Slicer, of which the following is a specification.

This invention has for its object a particularly simple and efficient vegetable cutter or slicer by means of which vegetables such as potatoes can be sliced, one way for German fried potatoes or in two directions into long blocks for French fried potatoes or in three directions into cubes.

15 This invention further has a particularly simple and efficient construction by which the vegetables are held while being sliced and are quickly released after being sliced. The invention consists in the novel features 20 and in the combinations and constructions hereinafter set forth and claimed.

In describing this invention, reference is had to the accompanying drawings in which like characters designate corresponding parts in all the views.

Figure 1 is a plan view of a preferable form of my vegetable cutter.

Fig. 2 is an elevation thereof, one of the knives being shown as elevated and the other 30 as in an intermediate position.

Fig. 3 is a sectional view showing the pins for holding the vegetables on the table as projected upwardly above the table and both knives swung downwardly into their 35 assumed position after cutting the vegetables.

This vegetable cutter comprises, generally, a table, means for holding the vegetables on the table and two gangs of knives movable 40 toward and from the table and arranged to cut at a right angle to each other.

1 designates the table which is supported in any suitable manner as on pillars or legs 2.

45 The table is here shown as formed with holes 3, these holes being arranged in rows in two directions at a right angle to each other, that is, they are arranged in rows extending lengthwise of the table and rows 50 extending transversely of the table; the table is also formed with transverse and longitudinal grooves 4 and 5, one set of grooves as 5 being deeper than the grooves 4, the deeper set being of greater depth than 55 the width of the knives movable thereto, plus the depth of the other grooves

4 in order that after one set of knives as the longitudinal set is brought downward through the vegetables and into the deeper grooves 5, the other set can also be brought 60 down into the shallower grooves 4 without striking the upper edges of the knives of the former set as shown in Fig. 3.

6 designates a knife frame carrying a set or gang of parallel knives 7 which for convenience are called longitudinal knives, these knives being movable into the deeper grooves 5, the frame 6 being hinged at 6^a to a bracket 8 projecting from the table.

9 is another knife frame carrying a set 70 of parallel knives 10 which for convenience are called transverse knives, these knives being movable into the shallower grooves 4. This frame is also hinged at 11 to brackets 12 projecting from the table. Each frame 75 is provided with a suitable handle 13 or 14 and is detachably secured in position by a removable hinge pin 15 or 16 in order that frames with differently spaced knives may be substituted.

The means for holding the vegetables on the table during the cutting operation and for stripping the cut vegetables after the cutting operation, comprises a plurality of spikes or pins 17 movable through the rows 85 of holes 3 between the knives 7, 10 these pins 17 being here shown as carried by a head 18 movable vertically below the table and having cutouts in the corners thereof which move along the legs 2.

The head 18 is actuated vertically in any suitable manner as by a lever 19 fulcrumed at 20 to one of the legs 2 and having its intermediate portion pivoted at 21 to a rod or stem 22 depending centrally from the table 95 head 18, this rod being guided in a suitable guide 23 carried by rods 24 extending inwardly from the legs 2.

Preferably, the lever 19 extends diagonally of the table, it being pivoted to one 100 leg 2 and extending through the slot 25 in the diagonally opposite leg.

In operation, the knife frames 6 and 9 are raised, the lever 19 operating to project the pins 17 above the surface of the table and 105 the vegetables placed on the pins; or the vegetables may be laid on the table, and the lever 19 operating to force the pins into the vegetable.

For slicing in one direction, as for German fried potatoes, one set of knives are brought down through the vegetables but

for slicing in two directions to form long blocks as for French fried potatoes both knives are brought successively down through the vegetables, the first knives thus 5 carried by the frame 6 moving into the deeper grooves 5 and below the surface of the table and the second set of knives 10 being brought down into the shallower grooves 4. The knife frames are then lifted 15 and the pins 17 withdrawn to strip the vegetables therefrom by pressing downward on the lever 19.

For cutting the vegetable into cubes they are removed from the spikes after slicing 15 with both knives 9, 10 and are turned so that the slices are arranged in horizontal position and one set of knives again brought down through the vegetables so that the sections of the vegetables are not cubes.

20 This vegetable slicer is particularly advantageous in that vegetables can be quickly sliced in any fashion and further in that it is simple in construction, consists of a small number of parts and readily cleaned.

25 What I claim is:

1. A vegetable cutter comprising a table, having a plurality of openings therethrough arranged in rows in two directions at a right angle to each other, a pair of knife frames 30 movable toward and from the table, substantially parallel knives carried thereby, the knives of one frame being arranged at an angle to the knives of the other and the knives of the frames being arranged to pass 35 between the rows of holes on the table, pins movable through the holes of the table, and means for moving the pins vertically, substantially as and for the purpose specified.

2. A vegetable cutter comprising a table 40 having a plurality of openings therethrough arranged in rows in two directions at a right angle to each other, a pair of knife frames movable toward and from the table, substantially parallel knives carried by the 45 frames, the knives of one frame being arranged at an angle to the knives of the other,

and the knives of the frames being arranged to pass between the rows of holes in the table, pins movable through the holes of the table, and means for moving the pins vertically, the table being formed with grooves for receiving the knives, substantially as and for the purpose set forth. 50

3. A vegetable cutter comprising a table, a plurality of pins movable through the 55 table, the pins being arranged in rows in two directions, means for moving the pins through the table, and gangs of knives movable toward and from the table, the knives of one gang being arranged at an angle to those of the other and said knives being arranged out of alignment with the rows of pins and movable between the rows of pins, the table being formed with grooves at a right angle to each other for receiving the 65 knives, substantially as and for the purpose described.

4. A vegetable cutter comprising a table having a plurality of openings therethrough arranged in rows in two directions at a right 70 angle to each other, a pair of knife frames movable toward and from the table, the knives of one frame being arranged at an angle to the knives of the other, and the knives of the frames being arranged to pass 75 between the rows of holes on the table, pins movable through the holes of the table, and means for moving the pins vertically, the table being formed with grooves for receiving the knives, the grooves for receiving one set 80 of knives being deeper than the grooves for receiving the other set of knives, the deeper grooves being of greater depth than the width of the knives plus the depth of the shallow grooves, substantially as and for 85 the purpose specified.

In testimony whereof, I have hereunto signed my name, at Syracuse, in the county of Onondaga, and State of New York, this 6th day of August, 1920.

ANNA E. RUSSELL.
